COMBINED HEATING AND COOLING SYSTEM

Lawrence E. Roberts, Toledo, Ohio

Application April 20, 1939, Serial No. 269,056

6 Claims. (Cl. 126—101)

This invention relates to room heating and cooling systems of the type used for cooling purposes in warm weather and for heating purposes in cool weather.

5 An object is to produce a new and improved system of the above character in which air is heated or cooled by the same device, which may be in the form of pipes in heat exchange relationship to the air and adapted to receive relatively warm or cool fluid according to the desired 10 temperature of the air introduced into the room.

Another object is to produce an apparatus which employs a series of pipes over which air is forced and through which a cooling or heating 15 fluid may be circulated or passed, depending upon the desired air temperature.

A further object is to produce a furnace of the hot air type by which the air is heated not only by heat from the products of combustion, 20 but also by contact with pipes through which fluid, such as water, is continuously circulated in a novel and efficient manner.

A still further object is to improve the efficiency of a hot air furnace by utilizing circulating hot water traveling through a closed system employing a dual arrangement of boilers.

Further objects of the invention will hereinafter appear, and for purposes of illustration but not of limitation, an embodiment of the invention is shown in the accompanying drawings, in which:

Figure 1 is a vertical sectional elevation of a heating and cooling apparatus;

Figure 2 is a transverse sectional view substantially on the line 2—2 of Figure 1;

Figure 3 is a diagrammatic view of the reservoir and tube arrangement showing by arrows the path of the liquid when the system is used for heating purposes;

Figure 4 is a vertical sectional elevation of the apparatus showing an end view or a view at right angles to that shown in Figure 1;

Figure 5 is an end view of the coil arrangement with the heads removed; and

Figure 6 is a top plan view of the coil arrangement.

The illustrated embodiment of the invention comprises an apparatus for heating or cooling air, as desired, the arrangement being such that in 50 cold weather, the air forced into the room may be warmed, and in warm weather the air introduced into the room may be cooled. As shown, 10 designates a substantially vertically elongate rectangular casing, to the upper end portion of 55 which on opposite side walls lead air inlet pipes

11 and 12. As will be readily understood, the pipes 11 and 12 may lead from cold air registers suitably arranged in the individual rooms. From the top wall of the housing 10 outlet pipes 13 extend to the individual rooms, it being understood that the number of pipes 13 may be varied as desired in accordance with the demands of service. 5

The air introduced into the housing from the inlet pipes 11 and 12 passes downwardly through filter units 14 and 18 of any suitable construction and thence into a fan housing 15, which may contain a suitable blower, such as a sirrocco fan, for forcing air under pressure through the system. The fan is driven by a belt 16 from an electric motor 17, which may be thermostatically controlled in any suitable manner, as by the room 10 temperature.

The blower forces the air upwardly through an air conditioning chamber 19, which will hereinafter be described, and into the air outlet pipes 13. Disposed in the chamber 19 in the path of movement of the air are a series of laterally extending flues 20 which are spaced from each other and through which the products of combustion pass to a discharge pipe 21, which may lead to the outside, preferably to a suitable chimney (not shown). The opposite end of the flues 20 communicate with a common lateral passage 22, which connect at each end with a boiler casing 23. Within the casing 23 at one side of the chamber 19 is a boiler 24 and within the casing 23 at the opposite side of the chamber 19 is a boiler 25. In each of the boilers 24 and 25 is a series of vertical flues 23a communicating at their upper ends with the passage 22. For heating the liquid, such as water, in each boiler is a gas 20 burner 26 disposed directly beneath the respective boiler.

The gas burner 26 on one side receives its supply of gas from a pipe 27, in which is disposed a thermostatically controlled valve 28. The pipe 27 is connected to a main gas supply pipe 29. The other burner 26 receives its supply through a pipe 30, which extends from the main line 29 and in

which is disposed a thermostatically controlled valve 31. The valves 28 and 31 operate automatically in accordance with the temperature of the water, which passes through the system of coils, as will hereinafter appear. 30

Suitably arranged above the flues 20 is a system of coils or pipes through which the liquid passes and about which the air, driven by the blower fan, passes after being forced through the passages 32 between the flues 20. Two sets of pipe units are provided for this purpose, and the ar- 35

arrangement and operation thereof is best illustrated in Figure 3. It will be apparent that the boiler 24 is connected by a tube 33 with the lower portion of a head 34, which is common to a plurality of vertically spaced tubes 35. The water passes to the left of Figure 3, as indicated by the arrows, through the tubes 35 into a head 36 at the opposite end thereof. The warm water, which has somewhat cooled, passes from the lower portion of the head 36 through a pipe 37 into the lower end portion of the boiler 25, where the temperature of the water is again increased. From the boiler 25 the water passes through a pipe 38 into the lower end portion of a head 39, which is common to a plurality of vertically spaced tubes 40. As indicated by the arrows on Figure 3, the water in the tubes 40 flows to the right and into a common head 41 at the opposite end thereof. At the lower end of the head 41 a pipe 42 leads to the lower end of the boiler 24, whereupon the above described liquid flow is repeated.

The number of these units may be increased, as desired, but in this instance two units are designated on Figures 5 and 6, by the reference characters A and B. As indicated in Figure 6, a plurality of closely spaced fins 43 may be connected to the pipes in order to effect a more efficient heat exchange relationship between the units and the air, which is forced therethrough by the blower fan, as will be readily understood.

Water may be supplied to the system from a pipe line 44, which may connect to the city water supply system. From the pipe 44 a branch 45 leads to a reservoir 46, in which the level is maintained by a suitable float control valve 47. From the reservoir 46 a pipe 48 is connected by branches 49 and 50 to the boilers. In the line 48 is a suitable hand valve 51 for controlling the water flow to the boilers. It will thus be apparent that the water flows by gravity to the boilers from the reservoir 46, so that the water pressure in the line 44 is not transmitted to the boilers. On the contrary, the pressure of the water in the reservoir 46 is sufficient to keep the desired supply in the boilers 44 and 45.

From the above description it will be apparent that the air which is drawn into the housing 10 through the pipes 11 and 12 by the blower is forced upwardly through the passages 32 between the flues and is partially heated, and thence is forced over the pipes 35 and 40 in the units A and B in order to be additionally heated and then passes out of the chamber 19 through the outlet pipes 13. In this manner very efficient use is made of the heat generated by the gas burners 26, it being understood that other forms of fuel may be used instead of gas for the desired purpose.

60 Any suitable control may be provided for operating the blower and burners. For example, the thermostats 28 and 31 may operate in accordance with the temperature of the liquid in the system so that when the temperature of the liquid drops below a predetermined minimum the burners may operate to supply additional heat. Other means, such as a control 52, may be suitably connected to be operated by the electric motor 17 so that the second burner will be turned up a predetermined period after the fan has operated in order to heat the additional volume of air supplied by the fan. Since the construction and arrangement of the particular form of controls are well known to those skilled in this art, further description thereof is not considered necessary.

For cooling the air, it will be readily understood that the burners 26 are rendered inoperative and the valve 51 is manually closed. From the reservoir 46 a pipe 53 has a portion 54 provided with branches leading to the upper end portions of the units A and B at one end so that the water can pass through the pipes 35 and 40 in the reverse manner to that above described in connection with the heating system. From one of the units leads a discharge pipe 58 to a suitable drain. Consequently, it will be understood that a constant supply of water may be introduced into the system which will cool the pipes, and, consequently, the air forced over them. As shown, a thermostatic switch 59 may be suitably connected to the motor 17 so that at the desired temperature the fan may be operated to force cool air throughout the system.

From the above description it will be apparent that the apparatus may be used either for heating air in an exceedingly efficient manner so that at a relatively low cost a large volume of warm air can be delivered to the various rooms in a house, or in summer the same system with very slight adjustments can be utilized for cooling purposes. Obviously, mechanical refrigeration could be used to cool the water introduced into the system, but in many places the temperature of the city water is sufficiently low to obtain satisfactory cooling.

It is to be understood that numerous changes in details of construction, arrangement and operation may be effected without departing from the spirit of the invention, especially as defined in the appended claims.

What I claim is:

1. A system of the character described having a chamber provided with spaced air inlet and outlet ducts, and means for creating a current of air from the inlet to the outlet ducts, means within said chamber for modifying the temperature of air passing therethrough, said temperature modifying means including two sets of tubes one disposed above the other, a pair of hot water boilers, means providing communication between the lower end of one set and the lower end of one boiler, means providing communication between the lower end of the other set and the upper end of said one boiler, means providing communication between the lower end of said first set and the upper end of the other boiler, and means providing communication between the lower end of said second set and the lower end of said other boiler, and means for heating the water in said boilers.

2. A system as claimed in claim 1 in which a boiler is arranged adjacent each end of the sets of tubes.

3. A system as claimed in claim 1 in which each of said sets comprises a plurality of spaced tubes and heads receiving opposite ends respectively of the tubes of each set, one head being at each set and being common to the tubes thereof.

4. A system as claimed in claim 1, including a constant level water reservoir, and means providing a gravity communication between said reservoir and said boilers.

5. A system as claimed in claim 1 in which said boilers comprise vertical flues, means providing a lateral passageway connecting all of said flues, a plurality of laterally extending spaced flues disposed in the path of movement of the air from said inlet to said outlet ducts and communicating at one end with said lateral passageway, a second lateral passageway communicating with the

other end of said lateral flues, and a discharge pipe communicating with said second passage-way.

6. A system of the character described having a chamber provided with spaced air inlet and outlet ducts, and means for creating a current of air from the inlet to the outlet ducts, means within said chamber for modifying the temperature of air passing therethrough, said temperature modifying means including two sets of tubes arranged in juxtaposed relation so that the air current passes successively from one set to the other, hot water boiler means, means providing communication between the lower end of one set and the lower end of said boiler means, means providing communication between the lower end of the other set and the upper end of said boiler means, means providing communication between the lower end of said first set of tubes and the upper end of said boiler means, and means providing communication between the lower end of said second set and the lower end of said boiler means, and means for heating the water in said boiler means. 5 10
